UNITED STATES PATENT OFFICE.

GEORGE E. MELLIN, OF NEW YORK, N. Y.

SKIP HOIST.

Application filed November 12, 1921. Serial No. 514,510.

To all whom it may concern:

Be it known that I, GEORGE E. MELLIN, a citizen of the United States, residing at Westerleigh, in the borough of Richmond, 5 of the city of New York, in the State of New York, have invented certain new and useful Improvements in Skip Hoists, of which the following is a specification, reference being had to the accompanying drawings, forming a part hereof.

This invention relates to skip hoists designed primarily for use in the transfer of ashes, coal and the like, from a pit to an elevated hopper. More particularly it is 15 concerned with a skip hoist which has a pivotally hung bucket, the truck of which travels on a continuous track which passes from a generally horizontal plane to a generally vertical plane. Operations in the 20 field which the improved construction fills have heretofore been practised with apparatus which is ill adapted to meet all requirements, is dirty, wasteful, inefficient and crude, resulting in poor current operations 25 and frequent repairs and replacements. It is proposed in accordance with the present invention to operate the truck of the skip hoist by means of fair rope leads which are so related to the truck and to the track-way 30 as to insure maximum head room, a clear pit, a pull always parallel to the direction of travel of the truck and the elimination of sagging and whipping in the cable. In accordance with the invention the skip hoist 35 is in the bight of a cable which is anchored at its opposite ends and passed over an operating drum, a plurality of sheaves being carried with the traveling truck to direct the rope along the track-way.

40 Still another object of the invention is to improve generally the construction of skip hoists having pivotally hung buckets in certain respects, some of which are particularly related to the improved system 45 of operating such hoists and some of which are generally applicable to such buckets and particularly useful in the loading and dumping operations thereon. One such improvement consists in the provision of a 50 hinged bail for the truck on which may be journaled the guide sheaves for the operating rope. Still another of these improvements has to do with the rollers at the sides 55 of the bucket frame which co-operate with

ping of the bucket during loading and which engage dumping cams mounted in their path to tip the bucket automatically when it is to be unloaded.

These and other objects and advantages 60 of the improvements herein will be brought out in greater detail hereinafter in connection with the detailed description of the embodiment illustrated in the drawings, wherein—

65 Figure 1 is a view partly in side elevation and partly in vertical section through a coaling pit and hoist-way with a skip hoist operable therein for conveying and elevating coal.

70 Figure 2 is a detail view in plan on a somewhat larger scale showing the improved truck for supporting the pivotal bucket.

75 Figure 3 is a view in side elevation of the bucket shown in Figure 2.

Figure 4 is a view partly in transverse section and partly in end elevation showing the bucket in position for coaling.

80 Figure 5 is a schematic view showing the leads for operating the traveling truck.

85 As indicated hereinbefore the improvements are concerned particularly with apparatus adapted to meet conditions wherein coal, ashes or the like, need to be conveyed along the horizontal for a distance and then elevated for deposit. Such a situation is indicated in Figure 1 wherein the coal pit is illustrated at *a* and a series of valve-controlled discharge hoppers at *b*, *b'*, etc., for 90 the discharge of coal to be transferred to the elevated hopper, indicated at *c*, from whence it may be supposed that the coal is ultimately deposited in a car *d*. The problem of providing a container which will travel in 95 both horizontal and vertical planes on an even keel is solved by having a pivotally hung bucket *e*, which is supported by trunnions *e'* on a truck frame, indicated generally at *f*, the wheels for which are shown at *f'*. The center of gravity of this pivotally hung bucket is, of course, below the axis of its pivotal support. Having this condition, nevertheless, the real problem of providing fair rope leads for moving the truck 100 along its tracks *g* presents itself. It has been proposed, for instance, to provide a single draw cable stretched along the pit between the tracks *g* and thence arranged over sheaves on the hoist-way to elevate the 105 110

bucket. This arrangement is obviously unsatisfactory and inefficient since it clutters up the track-way with sheaves, reducing the effective head room, permits the cable to sag 5 and whip, and in changing direction imposes a pull on the truck which is entirely out of line with its direction of travel. In accordance with the present invention, these objections are entirely eliminated and supplanted by a system which offers numerous 10 advantages. The truck *f* carries at its front and rear sides a plurality of sheaves *h*, *h'*, *h²*, *h³*, shown as arranged in pairs for the purpose of receiving over them the operating 15 cable *i* and directing the leads thereof along the pit in proximity to the tracks *g*. Considering for the moment the sheaves *h*, *h'* at the front end of the truck, it will be seen that the leads of the cable pass over 20 guide rolls *k* supported along the sides of the track-way and thence over other sheaves, indicated in Figure 5, at *k'* to change the direction of pull when the truck strikes the elevator *l*. Since the guide rollers *k*, *k'*, *k²*, 25 etc. for the operating cable *i* are, wherever found, always substantially in the plane of the track *g*, it necessarily follows that the direction of pull of the cable as applied to the truck through the front sheaves *h*, *h'* is 30 always in the plane of travel of the truck. Further, this condition insures the elimination of the whipping and sagging of the cable and a free track-way and pit with maximum head room throughout. In Figure 35 5, the cable *i* is shown as passing over idler sheaves *k²* to a hoisting drum *k³* and finally over idler sheaves *k⁴* around the sheaves *h²*, *h³* at the rear of the truck, for anchorage at its dead end. This arrangement 40 places the truck in the bight of the cable and, of course, movement in one direction is compensated for correspondingly by paying out in the other direction. At all times the leads are fair whether the truck 45 be traveling forward or backward.

An improvement which has been found desirable has to do with the mounting of the several sheaves *h*, *h'*, *h²*, *h³*, in pairs in hinged bails *m*, *n*, at the front and rear of 50 the truck respectively. The frames *m'*, *n'* of these bails, respectively, are of such form as to permit the respective pairs of sheaves to be journaled freely therein and are held in proper relation to the line of pull of the 55 cable and to the truck frame by means of supplemental rollers *m²*, *n²*, respectively, which ride along the tracks *g*. The pull of the cable *i* is impressed directly on these bails depending upon the direction of travel 60 of the track. In changing direction from the horizontal to the vertical, or vice versa, it will be evident that the pivoted frames *m'*, *n'* conform to the line of pull and changed direction in accordance with the 65 thrust to be transmitted to the truck. In

this way all lateral stresses are entirely eliminated and the principal advantages of the improvements as described hereinbefore are insured since the line of pull is always kept in the plane of travel of the truck. 70

As shown most clearly in Figures 2 and 3, the frame of the bucket *e* carries thereon below the trunnions *e'* a plurality of rollers *e²* at its opposite sides which, when the bucket is in loading position, may co-operate 75 with guard rails *o* mounted at the sides of the pit *a*. It will be unnecessary to duplicate these rolls and guard rails, but at all events, the effect thereof will be to prevent the bucket from tilting about its trunnions 80 *e'* through the engagement of the rollers with the guard rails, during loading. These rollers in the improved construction have not only been made to serve the purpose described but, in addition, bring about the 85 dumping of the bucket when it has reached its proper position with relation to the hopper *c* or other point of deposit. To this end, a dumping cam plate is shown on the elevator at *l'* in such relation to the track *g* 90 as to be engaged by the oncoming roller *e²* of the bucket *e* when the car reaches that point. Continuous movement of the truck with the appropriate roller *e²* engaged with the cam *l'* will cause the bucket to tilt about 95 its trunnions *e'* and deposit its charge automatically. Movement of the truck in the contrary direction will permit the bucket to return to normal position under the influence of gravity. 100

From the description given, it will be apparent that while the principal feature of the invention has to do with the operating mechanism for the skip hoist, the other improvements addressed to its construction are 105 advantageous in practice but may be employed either alone or in combination with the other features without departing from the spirit of the invention.

I claim as my invention: 110

1. In a skip hoist installation, in combination with a horizontal and inclined track-way, a truck traveling thereon, a bucket pivotally hung on the truck, an operating cable for the truck, and a plurality 115 of sheaves mounted on the truck and around which the cable passes to maintain fair leads of the cable in proximity to the tracks.

2. In a skip hoist installation, in combination with a horizontal and inclined track-way, a truck traveling thereon, a bucket pivotally hung on the truck, an operating cable for the truck, a plurality of sheaves mounted on the truck and around which the cable passes to maintain fair leads of the 120 cable in proximity to the tracks, and guide rolls for the cable supported in proximity to the tracks below the level of the truck. 125

3. In a skip hoist installation, in combination with a horizontal and inclined track- 130

way, a truck traveling thereon, a bucket on the truck, a plurality of spaced guide sheaves mounted at the front and rear of the truck, respectively, a single operating cable anchored at its ends at opposite sides of the span of travel of the truck and passing around the sheaves at opposite ends of the truck, and an operating drum over which the cable passes to move the truck 10 in the bight of the cable to and fro along the track-way.

4. In a skip hoist installation, in combination with a horizontal and inclined track-way, a truck traveling thereon, a bucket 15 pivotally hung on the truck, an operating cable for the truck, pivoted bails at the front and rear of the truck, and sheaves carried on said bails adjacent the tracks, respectively, and around which the operating 20 cable passes with fair leads in proximity to the tracks.

5. In a skip hoist installation, in combination with a horizontal and inclined track-way, a truck traveling thereon, a bucket 25 pivotally hung on the truck, an operating cable for the truck, pivoted bails at the front and rear of the truck, sheaves carried on said bails adjacent the tracks, respectively, and around which the operating cable passes 30 with fair leads in proximity to the tracks,

and rollers on said bails adapted to run on the tracks.

6. In a skip hoist installation, in combination with a horizontal and inclined track-way, a truck traveling thereon, a bucket 35 pivotally hung on the truck, an operating cable for the truck, pivoted bails at the front and rear of the truck, sheaves carried on said bails adjacent the tracks, respectively, and around which the operating cable passes 40 with fair leads in proximity to the tracks, rollers on said bails adapted to run on the tracks, and guide rolls for the leads of the cable supported at spaced intervals in proximity to the tracks. 45

7. In a skip hoist installation of the character described, in combination with the track-way, a truck to travel thereon, a bucket pivotally hung on the truck, a plurality of rollers carried on the bucket below 50 the pivotal axis, a guard rail overlying the said rollers when the truck is in loading position to prevent tilting of the bucket, and a dumping plate adapted to be engaged by one of said rollers for tilting of the bucket 55 when at the dumping point.

This specification signed this 9th day of November, A. D. 1921.

GEORGE E. MELLIN.
